CLAIM

I claim the ornamental design for a handle, as shown and described.

DESCRIPTION

FIG. 1 is a perspective view of the handle of this invention as seen from the top, rear and left side of the handle.

FIG. 2 is a left side elevation view of the handle, the right side view being a mirror image.

FIG. 3 is a top plan view of the handle.

FIG. 4 is a front elevation view of the handle.

FIG. 5 is a rear elevation view of the handle.

FIG. 6 is a bottom view of the handle; and,

FIG. 7 is a perspective view of the handle of FIG. 1 of this invention with additional environmental features as seen from the top, rear and left side of the handle.

The broken lines in the figures depict environmental subject matter and do not constitute a part of the claimed design.
